Primary Examiner — Dana K Weiland*Assistant Examiner* — Mary Claire Ramirez(74) *Attorney, Agent, or Firm* — Jonathan M. D'Silva; MMI Intellectual Property(57) **CLAIM**

The ornamental design for a kennel divider, as shown and described.

DESCRIPTION

FIG. 1 is a perspective view of a kennel divider showing the new design in a kennel;

FIG. 2 is another perspective view of the kennel divider in the kennel of FIG. 1 showing the kennel partially broken away;

FIG. 3 is a top view of the kennel divider;

FIG. 4 is a right side view of the kennel divider;

FIG. 5 is a front view of the kennel divider;

FIG. 6 is a bottom view of the kennel divider;

FIG. 7 is a back view of the kennel divider; and,

FIG. 8 is a left side view of the kennel divider.

The broken line showing of the kennel in FIGS. 1 and 2 is for the purpose of illustrating environment and forms no part of the claimed design.
